UNITED STATES PATENT OFFICE

2,484,719

RACK FOR PHONOGRAPH RECORDS

Lee McGuire, Lexington, Ky.

Application December 20, 1945, Serial No. 636,122

2 Claims. (Cl. 211—40)

1

The present invention relates to new and useful improvements in racks for displaying phonograph records in a convenient position for inspection and selection thereof.

More specifically, the invention embodies a phonograph record rack or stand embodying a ring member from which a plurality of arms project radially and connected to the ring for horizontal swinging movement, the arms having means for suspending envelopes containing a phonograph record or for suspending a frame within which a phonograph record album may be placed whereby a large number of the records may be supported in a position for convenient inspection and selection.

An important object of the present invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a top plan view.

Figure 2 is a side elevational view.

Figure 3 is a top plan view embodying a modified construction.

Figure 4 is a side elevational view thereof.

Figure 5 is an enlarged side elevational view of one of the arms for suspending the records thereof and with the supporting ring shown in section.

Figure 6 is a sectional view taken substantially on a line 6—6 of Figure 5.

Figure 7 is a side elevational view of one of the arms for supporting a phonograph record album and

Figure 8 is an end elevational view thereof.

Referring now to the drawings in detail and first with respect to the form of the invention illustrated in Figures 1 and 2, the numeral 5 designates the rack or stand generally which includes a plurality of posts 6 to which upper and lower rings 7 and 8 are attached, the rings being positioned outwardly of the posts.

The rings are of channel-shaped cross section with the flanges 9 thereof disposed in vertically spaced relation with respect to each other and having aligned circumferentially spaced openings 10 formed therein.

The openings 10 are adapted to rotatably re-

ceive the down turned inner ends 11 of arms 12 which project radially from the rings and are supported on the rings for horizontal swinging movement of the arms.

Each of the arms 12 are provided with a pair of substantially U-shaped hooks 13 invertedly arranged for straddling the arms and having outwardly turned ends 14 forming hooks adapted for engagement in reinforced eyes 15 at the open edge of an envelope 16 within which a phonograph record 17 is placed, the envelope 16 with the records 17 therein thus being suspended from the arm.

The envelopes 16 are usually formed with openings 18 in the opposite sides thereof by means of which the title of the record contained in the envelope may be viewed, or if desired, the envelope may have the title of the record printed or otherwise displayed thereon.

From the foregoing it will be apparent that a great number of records may be suspended in a position from the arms 12 by the upper and lower rings 7 and 8 and in a position for convenient inspection by prospective purchasers or users of the records.

In the form of the invention illustrated in Figures 3 and 4, the upper and lower rings 19 and 20 supported on the posts 21 are of tubular construction and likewise have the circumferentially spaced openings 22 formed therein and in which the inner down-turned ends 11 of the arms 12 may be placed in a manner as heretofore explained.

In the form of the invention illustrated in Figures 7 and 8, one of the ring members is shown at 23 and supported on the posts 24, the ring member having the openings 25 therein for receiving the down-turned inner end 26 of the arm 27.

An inverted channel-shaped member 28 is welded or otherwise fixedly secured to the underside of the arm 27 and from the sides of which rods 29 extend downwardly for supporting a lower channel-member 30.

A phonograph record album 31 is adapted for sliding in the outer ends of the channel members 28 and 30 for supporting the album thereon.

Accordingly, the phonograph record album may be supported from the arms 27 in the same manner as the envelopes 16 are supported on the arms 12.

The outer ends of the arms 12 and 27 may be protected by a rubber or other suitable cap 32.

In view of the foregoing description taken in conjunction with the accompanying drawings it is believed that a clear understanding of the con-

struction, operation and advantages of the device will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims. 10

I claim:

1. A phonograph record holder comprising a stand including a pair of spaced similar upper and lower annular members, posts attached directly to and supporting the members in a horizontal 15 position, arms pivoted to the upper member for horizontal swinging movement, and means for suspending one or more records from the arms.

2. A phonograph record holder comprising a stand including a pair of spaced similar upper and lower annular members, posts attached directly to and supporting the members in a horizontal 20 position, arms pivoted to the upper member for horizontal swinging movement, and a rack

attached to each arm and including upper and lower opposed channel members adapted to receive a record album therein, the upper channel members being rigidly attached to said arms to extend along the same and having end depending rods supporting the lower channel members.

LEE McGuIRE.
